DISPLAY CABINET

Gordon L. Freedman, Charlevoix, Mich., assignor to Freedman Artcraft Engineering Corp., Charlevoix, Mich., a corporation of Michigan

Filed Nov. 16, 1967, Ser. No. 9,440

Term of patent 14 years

U.S. Cl. D80—11

Int. Cl. D6—01

Fig. 1

FIG. 2

FIG. 3

FIG. 4

FIGURE 1 is a perspective view taken from the front and one side of a display cabinet showing my new design, the opposite side being a mirror image of the side shown.

FIGURE 2 is a top plan view thereof.

FIGURE 3 is a bottom plan view thereof.

FIGURE 4 is a rear elevational view thereof.

I claim:

The ornamental design for a display cabinet, substantially as shown.
